ELIJAH HORTON, OF OKEE, WISCONSIN.

Letters Patent No. 74,363, dated February 11, 1868.

IMPROVEMENT IN WAGON-SPRING.

The Schedule referred to in these Letters Patent and making part of the same.

TO ALL WHOM IT MAY CONCERN:

Be it known that I, ELIJAH HORTON, of Okee, in the county of Columbia, and State of Wisconsin, have invented a new and useful Improvement in Wagon-Springs; and I do hereby declare that the following is a full, clear, and exact description thereof, which will enable those skilled in the art to make and use the same, reference being had to the accompanying drawings, forming part of this specification.

This invention relates to a new and improved method of applying springs to wagons, whereby the ordinary lumber-wagon is rendered suitable for the transportation of many articles to which it is not adapted as it is ordinarily used; and the invention consists in arranging stirrups to the bolsters, which are made to support rubber springs, as will be hereinafter described.

Figure 1 is a longitudinal side view of an axle and bolster, with springs attached, after my plan.

Figure 2 is a cross-section of fig. 1, through the line x x , showing the stirrup and the method of securing the springs.

Similar letters of reference indicate corresponding parts.

A represents the axle of the wagon. B is the bolster. C represents the stirrup on the bolster. D represents the rubber spring. E represent bars or cross-pieces, which are supported by the springs, and which, in turn, support the bottom of the wagon-box. These cross-pieces E are connected together by ties, marked *a* in the drawing, and they are secured to the rubber springs by metallic cups, marked *b*, which set over the upper end of the spring, as seen in fig. 2. The stirrup C is formed something like a yoke, as seen in fig. 2, and it sets over the bolster, so as to form suitable seats for the springs, without in any manner impairing the strength of the bolster. F represents the wagon-stakes. The ties *a*, which cement the cross-bars E, are notched on to the stakes, so that the bars or cross-pieces and the tops of the springs are kept in position by the stakes, through which the stop-pins, *f*, pass. By removing one of these pins *f*, the cross-pieces, springs, and stirrups can be, at any time, removed from the wagon. The springs D are simply rubber blocks, formed for the purpose, which are secured in their places by the flanges which surround their ends, and by the tongues or spikes *e*, which penetrate them, as seen in the drawing.

It will be seen that this improvement can readily be applied to lumber-wagons now in use without altering or disturbing any of the parts, thus making them spring-wagons, when it may be desired to have them so.

Having thus described my invention, I claim as new, and desire to secure by Letters Patent—

1. The stirrup C, constructed and applied substantially as shown and described, for the purposes set forth.
2. In combination with the stirrup C, the rubber spring D, the cross-bars E, the ties *a*, and the cups *b*, arranged substantially as shown and described, for the purposes specified.

ELIJAH HORTON.
